DESIGN FOR A GAME BOARD

Frank Erznoznik, Pontiac, Mich.

Application March 15, 1945, Serial No. 118,492

Term of patent 14 years

(Cl. D34—5)

To all whom it may concern:

Be it known that I, Frank Erznoznik, a citizen of the United States, residing at Pontiac, in the county of Oakland and State of Michigan, have invented a new, original, and ornamental Design for a Game Board, of which the following is a specification, reference being had to the accompanying drawing, forming part thereof.

I claim:

The ornamental design for a game board, as shown.

FRANK ERZNOZNIK.
